UNITED STATES PATENT OFFICE.

WALTER A. CROWDUS AND HENRY M. SUTTON, OF DALLAS, TEXAS.

ELECTRIC-ARC LAMP.

SPECIFICATION forming part of Letters Patent No. 360,377, dated March 29, 1887.

Application filed October 1, 1886. Serial No. 215,059. (No model.)

To all whom it may concern:

Be it known that we, WALTER A. CROWDUS and HENRY M. SUTTON, both citizens of the United States, and residents of Dallas, county 5 of Dallas, State of Texas, have invented certain new and useful Improvements in Electric-Arc Lamps, of which the following is a specification.

In another application for United States 10 Letters Patent filed by us simultaneously here-with, under Serial No. 215,060, we have de-scribed and claimed an improvement in elec-tric-arc lamps, whereby the electric current, when the carbons are in contact, is divided be-tween the main-coil or solenoid circuit and a 15 cut-out circuit, the inductive action on a ver-tically-moving core located within the solenoid then being sufficient to impart an initial move-ment to the core, which breaks the cut-out cir-cuit. The whole of the current is thus caused 20 to flow through the main-coil circuit, the ac-tion on the core then being such as to further raise it and cause a clutch carried thereby to lift the upper-carbon rod and establish the arc 25 between the carbons.

The invention forming the subject-matter of this application embraces the same principle of operation by means of a differentially-wound hollow electro-magnet having the cut-out resistance-circuit also wound thereon, and 30 an iron armature fitted to move freely within the magnet and provided with a clutch for actuating the upper-carbon rod, which slides through the core.

This invention also embraces improved 35 means for utilizing a part of the magnetic field of the electro-magnet to act as a retard-ing medium or a brake to the carbon-holder, which consists of a system of gear-wheels pro-vided with a ratchet and pawl, as in the cor-responding device of our before-mentioned ap-40 plication, actuated from rack-teeth cut in the side of the upper-carbon rod, on the last spin-dle of which is adjustably secured a disk of 45 soft iron or other magnetic material, so located as to be within the influence of the magnetic field of one end of the electro-magnet. The 50 retarding action on this disk by induction is such as to hold up the carbon rod through the medium of the train of gears as long as the electric arc is of normal working length; but

upon the weakening of the magnetism, due to variation in the arc, the retarding influence on the disk is lessened, allowing it to be ro-tated by the carbon rod as it falls to bring the 55 arc to its normal working resistance. The ac-tion of this brake or retarding-disk, influenced simply by the lines of force of the magnetic field, is so delicate that the feed-controlling device responds immediately to the slightest 60 changes in the arc.

The holder for the lower carbon consists of a screw-jointed tube, in which the carbon is held by a clamping-screw, and is provided with two flanges adapted to clamp the tube in 65 an opening formed in the lower part of the lamp, thus constituting a simple and effective means for setting the lower carbon; but, to de-scribe our invention more particularly, we will now refer to the accompanying drawings, in 70 which—

Figure 1 is a central vertical section of our improved arc-lamp. Fig. 2 is a side view of the upper part of the lamp, showing the frame in section. Fig. 3 is a plan view of the same 75 cut on the line *xx*, Fig. 2; and Fig. 4 is a plan view of the lower-carbon holder.

a and *a'* are the side rods, screwed into the ring *b* at their lower ends, and connected by insulated joints to the plate *c* at their upper 80 ends. This plate *c* is fastened to the top plate, *c'*, by the posts *c²* *c'*; and the casing or cover *d* fits over the plates *c* and *c'*, and is held up by screws passing into the posts *c²* *c'*. The tube 85

d' screws into a neck on the plate *c'*. The upper-carbon-holding rod *e*, to which is secured the carbon *e'*, passes centrally through the operating mechanism of the lamp, comprising the hollow iron armature *f* and the iron core of the electro-magnet provided 90 with iron heads *g²* *g³*. On this iron core is wound the main coil *g*, included in the arc-cir-cuit. To the lower end of the armature *f* is connected the clutch by which the carbon rod *e* is raised, constructed and operating in a man-ner similar to that described in our before-mentioned application, and consisting of a split tube, *p*, disks *i* and *i'*, spring *i'*, and ad-justing-screws *i²* *i³*.

The fine-wire differential coil *f* is placed in 100 this lamp on the iron core *g²* of the electro-magnet, and is shown wound partly inside and

partly outside the main coil g . The cut-out circuit j' , which is equal in resistance to the main coil, is also placed on the outside of the main coil, and one end is joined to the insulated block j , carried by the armature f , and the other end by line k' to the binding-post k , which is fastened to the plate c' by an insulated connection. The block j makes contact with the disk i^2 , which is electrically connected 5 to the plate c of the frame, the flexible cord e^2 joining said plate to the carbon-holder e . The other binding-post, l , is connected electrically to the frame by being secured to the plate c' . The main coil g is placed in the arc-circuit by its end g' , joined to the rod a , and its other end to the wire k' ; and the fine-wire differential coil f' is connected so as to be permanently in circuit by being joined to the disk i^2 and the wire k' . By this arrangement of the various coils, which are connected in their respective circuits to induce similar polarities at their adjacent ends, the magnetic action on the armature f , the operation of the clutch carried thereby, and the 15 manner in which the cut-out circuit is made and broken will be fully understood, it being borne in mind that control of the upper carbon, when feeding to maintain the arc constant, is had by means independent of the arc-forming clutch, which means in this lamp consists of the soft-iron disk o , secured to the last shaft of a system of gear-wheels, $m m^2 m^3 n n^2 n^3$, the first wheel, m , of which meshes into a rack formed on the side of carbon-holding rod 20 e . The gears of this system operate as in the similar system shown in our before-mentioned application—viz., the ratchet-wheel m^3 allows the carbon rod e to be raised, either manually or by the core f of the magnet, without imparting motion to any wheels in the system other than the wheel m and ratchet-wheel m^3 ; but all the wheels, with the retarding-disk o , are caused to rotate when the carbon rod e falls. This disk o is located, as shown, with one of its faces 25 opposed to the edge of the upper iron flange, g' , of the electro-magnet, and is thus always under the influence of the magnetic field; and to provide for adjusting it within the part of the field which will exert sufficient retarding or 30 holding power thereon to uphold the upper carbon when the arc is burning normally, it is secured to the last shaft, n^4 , of the train of gears by the set-screw o' , passing through its hub.

55 When the disk o is properly adjusted, the least decrease of intensity of the magnetic field, due to an increase of resistance in the arc, allows the disk to be gradually rotated by the weight of the upper carbon and its rod until 60 the magnetic field again reaches its normal intensity.

When the carbons are consumed nearly to the holders, the descent of the upper-carbon rod e beyond a certain point is prevented by 65 leaving the upper part of the rod plain without

rack-teeth, so that the last tooth becomes locked in the wheel m . The arc then becoming abnormally long, the core f will fall its full distance, bringing the insulated block j in contact with the disk i^2 , and thus short-circuit the arc 70 by allowing the current to pass through the cut-out circuit j' .

The holder for the lower carbon, p , consists of a tube, q , provided with a flange, q' , arranged to bear against the lower side of the 75 ring b , its main portion, in which the carbon is held by the thumb-screw q^2 , projecting below the lamp-frame. Another flange, r , provided with a screw-threaded neck, rests on the top of the ring b , with its threaded neck fitting 80 into the top of the tube q . The tube q has considerable play in the ring b , thus permitting the carbon p to be placed directly under the carbon e . It is rigidly held in position by simply rotating it, and thereby drawing the 85 flanges q' and r together. The adjacent surfaces of the flange r and ring b are preferably roughened or corrugated to prevent the flange from rotating.

Having now described our invention, what 90 we claim, and desire to secure by Letters Patent, is—

1. In an electric-arc lamp, in combination, an electro-magnet, three electrical circuit-wires wound thereon, one constituting the 95 main coil included in the arc-circuit, one of fine wire forming the differential coil always in circuit in shunt around the arc, and the other in a cut-out circuit having a circuit-breaker, and an armature actuated by the 100 electro-magnet, provided with a clutch for forming the arc, and arranged to operate the circuit-breaker of the cut-out circuit, substantially as and for the purpose set forth.

2. In an electric-arc lamp, in combination, 105 a vertical hollow cored electro-magnet, a hollow cylindrical armature fitted to move freely therein, a carbon-holding rod sliding freely through the armature, a clutch carried by the armature and caused to grip the rod when the 110 armature is raised, a fine-wire coil wound differentially, a coarse-wire coil included in the arc-circuit, and a coil in a cut-out circuit whose resistance is about equal to that of the main coil, all three circuits being placed over 115 the iron core of the electro-magnet, and a circuit-breaker in the cut-out circuit, one part of which is carried by the armature, and the cut-out circuit closed thereby after the clutch carried by the armature is caused to 120 release the carbon rod, substantially as set forth.

3. In an electric-arc lamp, the combination, 125 with the actuating electro-magnet, the armature-core provided with a clutch, the carbon-holder passing through the armature-core, and a train of gears connected thereto so as to rotate therewith, of an iron disk secured to one of the axles of the train of gears and located within the field of the electro-magnet with one 130

of its sides facing one of the heads of the magnet and acting as a brake to retard the feed of the carbon rod, substantially as set forth.

4. In an electric-arc lamp, in combination, 5 the hollow electro-magnet $g g^2 g^3$, the hollow core f , provided with a clutch at its lower end, the carbon-holding rod e , carried by said clutch, the train of gear-wheels driven by rack-teeth on the rod e , and the iron disk o , ad-
10 justably connected to one of the shafts of the train of gears and located with one of its sides facing the head g^3 of the electro-magnet, sub-stantially as set forth.
